WILLIAM J. BLANKENBERG.

INVENTOR

BY *John J. Sculley*.

ATTORNEY

UNITED STATES PATENT OFFICE.

WILLIAM J. BLANKENBERG, OF BUFFALO, NEW YORK, ASSIGNOR TO THE PERFECT PROJECTOR MACHINE COMPANY, OF BUFFALO, NEW YORK, AN UNINCORPORATED STOCK-ISSUING COMPANY ORGANIZED BY A DECLARATION OF TRUST UNDER THE COMMON LAW OF NEW YORK.

MOTION-PICTURE-PROJECTING MACHINE.

Application filed September 24, 1920. Serial No. 412,604.

To all whom it may concern:

Be it known that I, WILLIAM J. BLANKENBERG, a citizen of the United States, residing at Buffalo, in the county of Erie and State of New York have invented certain new and useful Improvements in Motion-Picture-Projecting Machines, of which the following is a specification.

This invention relates to motion-picture-projecting machines and more particularly to a machine adapted for operation with an endless strip of film and essentially characterized by a single film-carrier and associated mechanism for the operation of the film.

The principal objects of the invention are to insure the regular and easy progress of the endless film through the machine and to eliminate appreciable pulling and buckling stresses on the film. In this way the invention promotes facility, certainty and reliability of operation and prevents all injury to the endless film.

Further objects are to provide easy accessibility to the film-carrier as occasion may require, thereby insuring facility in removing, inserting and exchanging films, and to provide a film-carrier and associated mechanism of simple structural nature and light and compact organization whereby the entire structure may be made as a portable unit which can readily be carried in the hand.

With the stated objects in view the invention consists in certain features of combination and organization appertaining to the film-carrier and the co-operating film-feeding mechanisms and also in structural details of said film-carrier and said mechanisms.

An embodiment of the invention is illustrated in the accompanying drawings, wherein:

Figure 1 is a side elevation of the projecting mechanism, the film-carrier and the film-feeding mechanisms.

Figures 2 to 5 inclusive are detail cross-sections on the respective lines 2-2, 3-3, 4-4, and 5-5 of Figure 1.

Figures 6 and 7 are detailed sections on the respective lines 6-6 and 7-7 of Figure 2.

Similar characters of reference designate

corresponding parts throughout the several views.

The operating parts, as shown in Figure 55 1, are enclosed in a box 1 which may be provided at one end with a lamp chamber 2. The invention is not concerned with details of the projecting mechanism which may be of any suitable construction. Such mechanism is indicated generally by the numeral 3 and is operated in the usual manner by a removable crank-handle 4.

The endless film 5 is supported in coil form on an annular carrier 6 which is normally located above and in front of the projecting mechanism and in a plane parallel to the focal axis. Said carrier, according to the invention comprises a vertical ring 7 which is provided with a series of 65 closely associated laterally directed film supporting projections 8 and with another series of radially directed film guiding or retaining projections 9. The projections 8 and 9 are preferably in the form of suitably 70 mounted anti-friction rollers. The coil of film surrounds the annular series of projections 8 and is retained in such positions by the rollers 9 and co-operating retaining bars 10 secured to the adjoining wall of the 75 box 1, the bars 10 overlying and engaging the coil of film at its sides.

The film carrier is movably mounted and in its normal operative position its inner side is closed by the bars 10, that is to say 85 these bars act as obstructions and prevent the lateral displacement of the film. By the movement of the film carrier away from the bars 10 its inner side is unobstructed and thereby the coil of film may be taken from, 90 or placed upon, the projections 8. In the construction preferred the ring 7 is provided with a forwardly projecting hingedly mounted supporting bracket 11 and the film-carrier is positively maintained in its normal position by a latch finger 12 secured to the adjacent side wall of the box and engaging over the ring 7. By moving said finger upward to the broken line position of Figure 1 the carrier is released and may 95 be swung to a position athwart the box in which position its inner side is open, that is to say, unobstructed.

The film, incident to its movement

through the projecting mechanism, is continuously drawn out from the center of the coil supported on the projections 8 and is continuously supplied to the rim of the coil.

5 According to the invention, in taking film from the coil and, preferably, in supplying film thereto, the film is positively operated by mechanism arranged in suitable adjacency to the points at which the film is 10 taken from and supplied to the coil.

At the take-off end of the coil the film-operating mechanism comprises a sprocket 13 having teeth arranged to engage the marginal perforations of the film and retaining rollers 14 to hold the film in contact with said sprocket and insure the effective engagement of said teeth. The rollers 14 are mounted on a stem 15 which is hinged at one end, as at 16, in order that it may 15 be thrown up or back, and is suitably retained in its lowered position as by a spring 17. The ring 7 carries a guide roller 18 which is located just inside of the annular series of projections 8 and is sufficiently 20 large to insure easy bending moments of the film as it passes from the coil to the sprocket 13. The film is looped about the periphery of said sprocket and beyond the rollers 14 disengages said sprocket and is 25 suitably directed to the projecting mechanism. Just below the roller 18 the ring 7 is slit, as at 19, whereby the portion of the film which extends between the sprocket 13 and the projecting mechanism may be 30 passed through the ring incident to the removal of the coil from the supporting projections 8 or to the insertion of the coil into the machine. In taking a film from the machine the rollers 14 are raised, the film disengaged from the sprocket 13 and the latch finger 12 disengaged from the ring 7; said ring is thereupon swung on its supporting hinge to a position athwart the box and in such position the coil of film is slid in the 35 direction of its axis from the projections 8 and the portion of the film at the other side of the ring 7 is passed through the slit 19, the film thereby being entirely free of its carrying or supporting means. The rest 40 of the film is disengaged from the projecting mechanism in any suitable or usual way. The operation of placing a coil of film in the machine is just the reverse of that described and is performed in the obvious 45 manner while the film carrier is positioned athwart the box 1.

At the supply end of the coil the film-operating mechanism 20 is similar to that described. It is preferred to interpose a 50 guide and tension bar 21 between the mechanism 20 and the film-carrier. As shown and preferred similar film-operating mechanism 22 is arranged to act on the film just before it passes into the projecting mechanism and in co-operation with the usual

devices for feeding it through such mechanism. The retaining rollers of the mechanism 20 and 22 are, of course, raised in the manner described to provide for the insertion or removal of the film.

70 The sprocket 13 and the similar sprockets of the other film-operating mechanisms 20 and 22 are operated by suitable gearing from the shaft 23 of the projecting mechanism and which carries the crank-handle 4. 75 For example the shaft 24 of the mechanism 20 is driven by spur gearing 25 from the shaft 23 and by spur and sprocket gearing 26 (Figure 7) drives the shaft 27 upon which the sprocket 13 is mounted. The 80 gearing which operates the mechanism 22 is generally similar and its illustration is, therefor, deemed unnecessary.

85 From the foregoing description it will be apparent that the stresses on the film are inconsiderable, and are uniformly distributed both throughout the coil and throughout the running lengths. The movements of the film are uniform at all points and are effected at a constant rate while there 90 are no unduly long unsupported portions to buckle or otherwise interfere with or retard the operation. The drawing clearly shows how all the working parts may be compactly arranged in a box which, in 95 practice, may be about the size of an ordinary suit case and may be readily carried in the hand from place to place.

Having fully described my invention I claim:

100 1. In a motion picture projecting machine, the combination of projecting mechanism having an operating shaft, annular means for revolvably supporting a vertical coil or film, said means being located in front of said mechanism and in a plane parallel to the focal axis and having an unobstructed side and an obstructed side, a support to which said means is hinged, stationary means effective in the operative position 105 of said coil supporting means to prevent the displacement of the film from said unobstructed side, positively acting film feeding means located within said coil as supported by said supporting means and with which 110 the inner convolution of the coil is engaged, said film feeding means having an operating shaft projecting through the unobstructed side of said supporting means, and gearing operatively connecting the operating 115 shafts of said projecting mechanism and said film feeding means to cause the latter to take film from the center of the coil, said annular supporting means being movable on its hinge toward and from the stationary 120 means.

125 2. In a motion picture projecting machine, the combination of projecting mechanism having an operating shaft, annular means for revolvably supporting a vertical

- coil or film, said means being located in front of said mechanism and in a plane parallel to the focal axis and having an unobstructed side and an obstructed side, a support to which said means is hinged, stationary means effective in the operative position of said coil supporting means to prevent the displacement of the film from said unobstructed side, positively acting film feeding means located within said coil as supported by said supporting means and with which the inner convolution of the coil is engaged, said film feeding means having an operating shaft projecting through the unobstructed side of said supporting means, other positively acting film feeding means located beyond the projecting mechanism and intermediate said mechanism and the coil and gearing operatively connecting the operating shaft of said projecting mechanism with both of said film feeding means to cause the first named film feeding means to take film from the center of the coil and to cause the last-named film feeding means to supply film to the rim of said coil, said annular supporting means being movable on its hinge toward and from the stationary means.
3. In a motion picture projecting machine, a hingedly mounted annular support for a vertical coil of film having an operative position wherein film is taken from the center of said coil, said support having an obstructed side and an unobstructed side, stationary means operative in the operative position of said support to prevent the displacement of the coil from the unobstructed side, said support permitting the free rotation of said coil and said coil being freely revoluble in the operative position of said support, a driven shaft located adjacent the unobstructed side of said support in the operative position thereof and positively acting film feeding means arranged within the coil and supported and operated by said shaft, said film feeding means taking film from the center of the coil and said support being movable on its hinge relatively to said film feeding means.

In testimony whereof I affix my signature.

WILLIAM J. BLANKENBERG.
